BY *J. C. Lindner,*
his ATTORNEY

UNITED STATES PATENT OFFICE

JOHN C. LINDNER, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed December 14, 1929. Serial No. 414,163.

This invention relates to electric interlocking systems for railroads, and more particularly pertains to cross protection means for such systems.

5 In interlocking plants, it is desirable to provide means in the central tower for continuously indicating the position and locked condition of the outlying track switches, so that the signals, governing the traffic over 10 a particular track switch, may be selected or controlled in accordance with the condition of that particular switch. In one type of system, this has been accomplished by controlling a three-position relay, located in the 15 tower, over a polarized line circuit extending from the associated switch. Such a switch repeating relay, sometimes called an SS relay, when controlled over a polarized line circuit, is of course provided with all the 20 desirable features of cross protection inherent in such a circuit, all of which is well known to those skilled in the art.

In accordance with the present invention, it is proposed to provide a switch machine 25 control system of the dynamic indication type which has the control of a switch repeating or SS relay super-imposed upon it by the use of alternating current. One object of the 30 present invention is to provide such super-imposed SS relay control in a manner to retain the inherent cross protection of a polarized circuit for the SS relay, and also to have this super-imposed control check the cross 35 protection of the switch machine control circuits. A further object is to provide protection for both the switch machine control and the SS relay control, from crosses with the control wires of other similarly operated 40 functions and also from crosses with foreign sources.

Other objects, purposes and characteristic features of the present invention will be in part obvious from the accompanying drawing, and in part pointed out as the 45 description of the invention progresses.

In describing the invention in detail, reference will be made to the single figure of the accompanying drawing, in which an interlocking system embodying the present invention has been shown in a diagrammatic

manner illustrating the control of two typical track switches of an interlocking plant and also the indication means associated therewith. The similar devices associated with each track switch will be designated by similar reference characters having the distinctive exponents *a* and *b* respectively.

With reference to the single figure of the accompanying drawing two main tracks, having rails 5 and 6 respectively, are shown interconnected by rails 7 of a crossover at each end of which are located track switches TS^a and TS^b respectively. These track switches TS^a and TS^b are normally set for main line traffic on their respective main tracks 5 and 6 and are controlled to reverse positions for crossover traffic by their respective switch machines SM^a and SM^b.

The switch machines SM^a and SM^b are of the usual reversible type, such for example as shown in the patent to W. K. Howe, No. 1,466,903, dated September 4, 1923. These switch machines include their respective pole changer contacts PC^a and PC^b and their respective pole changer coil contacts PCC^a and PCC^b. Also, point detector contacts PD^a and PD^b are associated with these respective switch machines and track switches.

Pole changer contacts PC^a include movable contacts 10 and 11, while pole changer contacts PC^b include movable contacts 12 and 13. These movable contacts of the respective switch machines make contact between certain pairs of fixed contacts when in normal extreme positions and make contact between other pairs of fixed contacts when in reverse extreme positions. The normal or reverse positions of these movable contacts are mechanically caused to be assumed in correspondence with the respective switch machine at the end of an operation, or are electrically caused to assume opposite positions during the operation of the switch machine, in a manner as set forth in the above mentioned Patent No. 1,466,903.

The pole changer coil contacts PCC^a and PCC^b include movable contacts 14 and 15 respectively which make contact between their respective pairs of fixed contacts when in normal extreme positions or in intermediate po-

sitions; and also movable contacts 16 and 17 respectively which make contact between their respective pairs of fixed contacts when in reverse extreme positions or in intermediate positions.

5 The point detector contacts PD^a include movable contacts 18 and 19 which assume normal or reverse extreme positions in correspondence with the track switch TS^a when it is locked, and assume intermediate positions during the operation of the switch or at such other times that it is unlocked. These movable contacts 18 and 19 make contact between respective pairs of fixed contacts when in normal extreme positions and make contact between certain other respective pairs of fixed contacts when in reverse extreme positions. A shunt contact 20 is actuated to a non-contacting position when the track switch TS^a 10 is in a normal locked position, and assumes a biased contacting position at any such time that the track switch is not in a normal locked position; and also, a shunt contact 21 is actuated to a non-contacting position when the track switch is in a reverse locked position, and assumes a biased contacting position at any such time that said track switch is not 15 in a reverse locked position.

Similarly the point detector contacts PD^b 20 are associated with the track switch TS^b and include movable contacts 22 and 23, also shunt contacts 24 and 25, which contacts have functions as above explained for corresponding parts of the point detector contacts PD^a.

35 The point detector contacts PD^a and PD^b may be operated by any suitable type of mechanism, such for example as shown in the patent to C. S. Bushnell, Patent No. 1,513,236, dated November 25, 1924 with the 40 shunt contacts added as shown, for example, in my pending application Ser. No. 385,172, filed August 12, 1929.

Local transformers LT^a and LT^b, located at the switches TS^a and TS^b respectively, are 45 supplied with suitable alternating current potential from a transmission line extending from the interlocking tower.

In the interlocking tower, relays SS^a and SS^b are provided to indicate the positions and 50 locked conditions of the associated track switches TS^a and TS^b respectively. This is accomplished by each SS relay having contacts which are controlled to either normal or reverse extreme positions in accordance with 55 the corresponding positions assumed by the associated track switches, and which assume biased deenergized intermediate positions when the track switches are in operation or at other such times that the track switches are 60 unlocked.

The relays SS^a and SS^b are of the two phase winding alternating current type, having line phase windings 30 and 31 respectively and local phase windings 32 and 33 respectively. 65 The local phase windings 32 and 33 are con-

tinuously energized from local transformers T^a and T^b respectively, which transformers are supplied with alternating current potential from the same transmission line which supplies the local transformers at the 70 switches. The line phase windings 30 and 31 are respectively governed by the point detector contacts PD^a and PD^b.

The usual control levers L^a and L^b are provided for controlling the respective switch machines SM^a and SM^b. These levers are provided with indication latch mechanisms IL^a and IL^b respectively which prevent the operation of the respective levers to full normal or full reverse positions from corresponding governing positions except after actuation of the associated indication magnets IM^a and IM^b. These indication latch mechanisms IL may be of any suitable type, such for example, as shown in the patent to J. D. Taylor, Patent No. 752,127, dated February 16, 1904. Safety magnets S^a and S^b are associated with their respective indication magnets IM^a and IM^b. The safety magnets S are designed to carry the full operating current of the switch machine, and provide that the indication magnets IM cannot actuate their armatures to release the indication latch mechanisms IL while such operating current is flowing due to the ratio of turns 80 between the two windings and due to the fact that the safety magnets have the advantage with the armatures against their pole faces. In accordance with the present invention, the safety magnets S prevent further false releasing of the indication latch mechanisms should crosses occur between the operating wires or between the next operating wire of a particular switch machine and some foreign source, all of which will be pointed out 85 more specifically hereinafter.

The levers L^a and L^b have associated therewith the usual tappet bars 35 and 36 respectively which are controlled by their respective cam slots 37 and 38 for controlling the usual mechanical interlocking between associated levers in a manner well known to those skilled in the art. The levers L are of the usual reciprocating type operating their respective movable contacts 25, 26, 27 and 28 to any one of four positions, namely, full normal positions, half normal positions, half reverse positions and full reverse positions in the order named as the levers are moved to the left from the normal positions shown. 110 These movable contacts make contact between their respective pairs of fixed contacts when in normal and half normal positions and make contact between certain other pairs of fixed contacts when in full reverse or half reverse positions.

In order that the respective levers L^a and L^b may be provided with indications which will not permit the operation of a lever to a position out of correspondence with its asso- 115 120 125 130

ciated switch machine, the indication selectors IS^a and IS^b are provided, being of the usual mechanical stick type.

Polarized cross protection relays P^a and P^b are provided to open the control circuits of the respective associated switch machines should a cross occur between the operating wires of a particular switch machine or between the next operating wire of a particular switch machine and some foreign source. These polarized cross protection relays may be of any suitable type, for example, as shown in my Patent No. 1,676,340 dated July 10, 1928.

Suitable resistances R^a and R^b are provided in multiple with the respective field windings F^a and F^b to reduce the alternating current impedance of the line circuits of the respective SS relays. Although the field windings F are of low resistance to the direct current operating power, they are of comparatively high impedance to the alternating current for the SS relays. Thus, these resistances R^a and R^b reduce the impedance values of the SS relay line circuits as well as tending to provide a better phase relationship as will be hereinafter pointed out. Also, these resistances R are preferably of a value equal to the alternating current impedance of the respective field winding which they shunt, but may have other values according to the circumstances to be met.

Suitable resistances 120 and 39 are provided to compensate for the varying lengths of line wires which extend between the interlocking tower and the switch locations. Also, these resistances provide means for obtaining suitable relative phase displacement between the local and line phase windings of the SS relays.

It is believed that the usefulness of such a system and the interrelated functions of the various devices will be better understood by further description being given from the standpoint of operation of the system taken as a whole.

Operation of the system

The control levers L^a and L^b are shown in their full normal positions with their respective switch machines SM^a and SM^b in corresponding positions. In accordance therewith, the relays SS^a and SS^b are energized in a manner to control their contacts to normal positions, which contacts may be used for the selection of the signals governing traffic over the associated track switches or for such other purposes as may be required in accordance with the usual interlocking practice. It is to be understood that it is unnecessary to show the means and manner of control accomplished by the contacts of the SS relays as such control forms no part of the present invention and may be varied to suit the particular circumstances of a given situation.

Only the operation and interrelation of the parts associated with the control lever L^a and switch machine SM^a will be described in detail, as the operation and interrelation of the parts and devices associated with the control lever L^b and the switch machine SM^b is identical in every respect. However, the interrelation between these two switch functions will be set forth in detail.

The local phase winding 32 of the relay SS^a is continuously energized with alternating current supplied by the local transformer T^a, while its line phase winding 30 is supplied with alternating current over its normal energizing circuit from the local transformer LT^a located at the switch machine. The local transformer LT^a is energized from the alternating current transmission line extending from the interlocking tower through point detector contacts PD^a which are in normal positions. This normal energizing circuit for the local transformer LT^a is traced as follows:—from one terminal of the alternating current source of electrical potential, through wire 40, contacts 18—41, wires 42 and 43, primary winding of local transformer LT^a, wire 44, shunt contact 21 in a contacting position, contacts 19—45, wire 46, resistance 120, wire 47, to the opposite terminal of the alternating current source.

The energization of the primary winding of local transformer LT^a causes the current induced in its secondary winding to flow in the normal energizing circuit of the line phase winding of the relay SS^a. This normal energizing circuit is traced as follows:—from the right hand terminal of the secondary of transformer LT^a, through wires 48 and 49, field winding F^a and resistance R^a in multiple, wire 50, contacts 10—51, wire 52, armature A^a, wires 53 and 54, contacts 11—55, wire 56, contacts 25—57, wire 58, contacts 59—60 of indication selector IS^a, wire 61, line phase winding 30 of relay SS^a, wire 62, windings of indication magnet IM^a, wire 63, windings of cross protection relay P^a, wire 64, contacts 65—66—67 of relay P^a, wire 68, to the left-hand terminal of the secondary of local transformer LT^a.

It is noted, that the usual practice is to supply the local phase winding of such an SS relay with a current having a relatively larger reactive component than the line phase winding, as the local current flows through short lead wires thus reducing the amount of power loss, while the line phase winding is usually provided with a current having a relatively larger resistive component as this current naturally has a resistive characteristic due to the length of line wire and is of considerably smaller value. This is of course done to give a suitable phase displacement between the local and line phase windings in order to produce sufficient torque to operate the relay contacts. However, in this case,

the line phase winding circuit includes the field winding F^a , the windings of indication magnet IM^a and the windings of polarized relay P^a all of which tend to change the phase angle of the line phase winding from a resistive current to a more reactive current. Such a condition would cause the relative instantaneous polarity in the line phase winding to be practically in phase with the relative instantaneous polarity of the local phase winding thus reducing the torque of the operating elements of the relay. This condition is met by providing the resistance R^a in multiple with the field winding F^a , which, for example, allows one-half of the line phase winding current to pass through it thereby adding to its resistive component. Also, the resistance 120 as well as being compensating means for the varying distance between the tower and the outlying switch machine, also adds to the resistive component of the line phase winding current.

Let us consider the operation of the system from the normal condition to the reverse condition, which is accomplished by the operation of the control lever L^a from its present normal condition to a half reverse position and thence to a full reverse position after the completed operation of the switch machine SM^a . The operation of the system from a reverse condition to a normal condition will not be described as it is merely an inverse function thereof.

Assuming that the lever L^a is moved to a half reverse position, the normal energizing circuit of the line phase winding 30 of the relay SS^a is broken at contacts 25-57 which immediately causes its contacts to assume neutral deenergized positions. Also, with the lever L^a in the half reverse position, the switch machine SM^a receives operating current from a suitable source of direct current potential, the opposite terminals of which are shown as positive and negative buses.

The reverse operating circuit of the switch machine SM^a is traced as follows:—from the positive bus of a suitable source of electrical potential, through wires 70 and 71, reverse operating winding 72 of indication selector IS^a , wire 73, contacts 26-74, wires 75 and 56, contacts 11-55, wires 54 and 53, windings of armature A^a , wire 52, contacts 10-51, wire 50, field winding F^a and resistance R^a in multiple, wires 49 and 48, secondary winding of local transformer LT^a , wire 68, contacts 67-66-65, wire 64, windings of polarized relay P^a , wire 63, windings of indication magnet IM^a , wire 62, line phase winding 30 of relay SS^a , wire 61, contacts 60-84 of indication selector IS^a , wire 85, contacts 25-86, wires 87, 88 and 89, contacts 11-90, wires 91 and 52, to the upper terminal of armature A^a . The dynamic current flowing in this circuit actuates the indication magnet IM^a but does not actuate the contact 66 of polarized cross-protection relay P^a , this because this relay P^a responds only to direct current of a particular polarity, namely to current flowing from right to left through its winding, it preferably being a polar relay of the permanent magnet type.

Also, with the track switch TS^a in a reverse locked position the movable point detector contacts 18 and 19 are operated to reverse extreme contacting positions which cause the shunt contact 21 to be operated to a non-contacting position. The primary winding of local transformer LT^a is thus energized through a circuit traced as follows:—from one terminal of the alternating current source, through wires 40 and 92, contacts 19-93, wire 44, primary winding of local transformer LT^a , wire 48, shunt contact 20 in a contacting position, wire 94, contacts 18-95, wires 96 and 46, resistance 120,

chine SM^a , and as soon as it has operated to unlock the track switch TS^a , the point detector contacts 18 and 19 are operated to intermediate non-contacting positions which allows the shunt contact 20 to assume a contacting position. The energization of the primary of the local transformer LT^a is thus discontinued and said primary winding is short circuited or shunted through wire 44, shunt contact 21 in a contacting position, wire 79, shunt contact 20 in a contacting position, and wire 43.

When the switch machine has completed the operation of the track switch TS^a and locked it in a reverse position, the movable contacts 10 and 11 of pole changer contacts PC^a are operated to reverse positions opening the reverse operating circuit of the switch machine at contacts 10-51 and 11-55. The final free run of the motor armature A^a , due to momentum, generates a dynamic current which serves both to bring the armature A^a to rest, and to provide energization of the indication magnet IM^a for releasing the indication latch mechanism IL^a which allows movement of the control lever L^a to a full reverse position. This reverse dynamic indication circuit for the switch machine SM^a is traced as follows:—from the lower terminal of armature A^a , through wire 53, contacts 10-82, wires 83 and 50, field winding F^a and resistance R^a in multiple, wires 49 and 48, secondary winding of local transformer LT^a , wire 68, contacts 67-66-65, wire 64, windings of polarized relay P^a , wire 63, windings of indication magnet IM^a , wire 62, line phase winding 30 of relay SS^a , wire 61, contacts 60-84 of indication selector IS^a , wire 85, contacts 25-86, wires 87, 88 and 89, contacts 11-90, wires 91 and 52, to the upper terminal of armature A^a . The dynamic current flowing in this circuit actuates the indication magnet IM^a but does not actuate the contact 66 of polarized cross-protection relay P^a , this because this relay P^a responds only to direct current of a particular polarity, namely to current flowing from right to left through its winding, it preferably being a polar relay of the permanent magnet type.

Also, with the track switch TS^a in a reverse locked position the movable point detector contacts 18 and 19 are operated to reverse extreme contacting positions which cause the shunt contact 21 to be operated to a non-contacting position. The primary winding of local transformer LT^a is thus energized through a circuit traced as follows:—from one terminal of the alternating current source, through wires 40 and 92, contacts 19-93, wire 44, primary winding of local transformer LT^a , wire 48, shunt contact 20 in a contacting position, wire 94, contacts 18-95, wires 96 and 46, resistance 120,

wire 47, to the opposite terminal of the alternating current source.

The current induced in the secondary of local transformer LT^a is of opposite instantaneous relative polarity in respect to that current induced when the point detector contacts PD^a are in normal positions, and flows in the reverse energizing circuit for the line phase winding 30 of the relay SS^a thus actuating its contacts from deenergized positions to reverse energized positions. This reverse energizing current for line phase winding 30 of relay SS^a is traced as follows:—from the right-hand terminal of the secondary of local transformer LT^a, through wires 48 and 49, field winding F^a and resistance R^a in multiple, wires 50 and 83, contacts 10—82, wire 53, windings of armature A^a, wires 52 and 91, contacts 11—90, wires 89, 88 and 87, contacts 25—86, wire 85, contacts 84—60 of indication selector IS^a, wire 61, line phase winding 30 of relay SS^a, wire 62, windings of indication magnet IM^a, wire 63, winding of polarized relay P^a, wire 64, contacts 65—66—67, wire 68, to the left-hand terminal of the secondary of local transformer LT^a.

During the operation of the switch machine SM^a, the movable contacts 14 and 16 of the pole changer coil contacts PCC^a are operated to their central intermediate contacting positions, which provides for the reversibility of the switch machine in midstroke by the operation of the control lever L^a to an opposite governing position. Such movement of the control lever applies energy to the opposite control wire which completes a circuit for the corresponding pole changer coil that operates the movable contacts 10 and 11 of pole changer contacts PC^a to opposite positions to close the opposite operating circuit. This is accomplished all in a manner as disclosed in the above mentioned Patent No. 1,466,903.

From the above description, it is obvious that the dynamic indication circuits and the energizing circuits for the line phase winding 30 of the relay SS^a are very similar in the various devices and contacts which they include. However, they differ in the character of currents, the sources of such currents and the devices which are acted upon by such currents. More specifically, the dynamic indication current is direct current generated by the revolving armature of the direct current motor included within the switch machine, while the energizing current for the SS^a relay is alternating current supplied to the circuit by a local transformer having its secondary winding included therein. The dynamic indication current actuates the indication magnet IM^a, but does not actuate the polarized relay P^a, as this relay requires the application of positive potential upon its right-hand terminal in order for its contacts to be actuated; and does not actuate the relay SS^a, as it

is of the two phase alternating current type and obviously cannot operate with the application of direct current. The alternating indication current for the SS relay flows through the same circuits but is of such a comparatively small value that it does not effect the indication magnet IM^a, or polarized cross protection relay P^a, but does actuate the line phase winding 30 of the SS relay.

Although the resistance R^a is in multiple with the field winding F^a, there is a very small value of the operating current which flows through R^a as it is of such high ohmic resistance in comparison with the ohmic resistance of the field winding. However, with the application of alternating current across the multiple circuit of the field winding and resistance, the alternating current impedance of the field winding in accordance with the frequency of the current is equal to the ohmic resistance of the resistance R^a. The alternating current thus divides equally between the two.

Assuming the switch machine SM^a and control lever L^a to be in normal positions, as shown, and that a cross C¹ occurs between the two control wires 56 and 88 of the switch machine SM^a, an unauthorized current would flow from the positive bus through wires 70 and 98, normal operating coil 99 of indication selector IS^a, wire 100, contacts 26—101, wire 88, cross C¹, wire 56, contacts 25—57, wire 58, contacts 59—60 of indication selector IS^a, wire 61, winding 30 of SS^a relay, wire 62, windings of indication magnet IM^a, wire 63, windings of polarized cross protection relay P^a, wire 64, contacts 65—66—76, wire 77, windings of safety magnet S^a, wire 78, to the negative bus. Current flowing through this circuit established by an accidental cross between the control wires of switch machine SM^a, operates the contact 66 of cross protection relay P^a to an upper position opening contacts 66—76, which opens both the normal and reverse operating circuits of the switch machine SM^a and also opens the cross circuit. During the existence of such a cross, as for example C¹, the current that flows in said circuit passes through the safety magnet S^a and indication magnet IM^a in series, thus preventing said current from actuating or falsely releasing the indication latch mechanism IL^a for reasons above pointed out.

Should the cross protection circuit for the switch machine SM^a, as above pointed out, for any reason be incomplete, it is obvious that the relay SS^a would be deenergized, as its normal and reverse energizing circuits include respectively the normal and reverse cross protection circuits of the switch machine. Thus, it may be said that the relay SS^a provides a check upon the cross protection of the switch machine SM^a.

Should a cross C² occur between the nor-

mal control wire 102 of the switch machine SM^b and the reverse control wire 56 of switch machine SM^a , the switch machine SM^a would not be operated due to the fact that 5 the cross protection relay P^a would be operated to open the control circuit. However, heretofore there has been the possibility that such a cross, between the control wires of 10 two such similarly controlled functions, would energize the indication magnet IM^a and falsely actuate the indication latch mechanism IL^a . This is prevented by the present invention inasmuch as the safety magnet S^a is included in series with indication magnet 15 IM^a if such a cross circuit occurs, which prevents the actuation of the armature of indication magnet IM^a to an energized position for reasons heretofore pointed out. This unauthorized circuit, established by a cross such 20 as cross C^2 , may be traced as follows:—from the positive bus, through wires 114 and 115, normal operating coil 116 of indication selector IS^b , wire 117, contacts 28—118, wire 102, cross circuit C^2 , wire 56, contacts 25—57, wire 25 58, contacts 59—60 of indication selector IS^a , wire 61, line phase winding 30 of relay SS^a , wire 62, windings of indication magnet IM^a , wire 63, windings of polarized cross protection relay P^a , wire 64, contacts 65—66—76, wire 77, windings of safety magnet S^a , wire 78, to the negative bus. The contact 30 66 of polarized cross protection relay P^a is actuated to an upper position opening the operating circuit of the switch machine SM^a at contacts 66—67—76, and opening the unauthorized circuit at contacts 65—66—76.

The safety magnet S^a is located in a key position which provides that it may always carry the operating current of its associated 40 switch machine SM^a ; and that it may be included in series with its associated indication magnet IM^a when any false or unauthorized circuit occurs which might falsely energize said indication magnet.

45 The safety magnets S have the further functions of preventing the energization of their associated SS relays from any other alternating current sources used to energize other similarly connected SS relays. This 50 may be explained by considering, for example, cross C^3 which might occur between the reverse operating wire 103 of switch machine SM^b and the reverse operating wire 56 of switch machine SM^a . With such a cross 55 circuit, the line phase winding 30 of relay SS^a would be falsely energized or falsely affected by the local transformer LT^b during the time that any such cross should occur, if it were not for the added impedance in the circuit 60 provided by the safety magnets S . This unauthorized circuit may be traced as follows:—from the right-hand terminal of the secondary of transformer LT^b , through wires 105 and 106, field winding F^b and resistance 65 R^b connected in multiple, wire 107, contacts

12—108, wire 109, windings of armature A^b , wires 110 and 111, contacts 13—112, wire 103, through the cross C^3 , wire 56, contacts 25—57, wire 58, contacts 59—60 of indication selector IS^a , wire 61, line phase winding 30 of relay SS^a , wire 62, windings of indication magnet IM^a , wire 63, winding of polarized relay P^a , wire 64, contacts 65—66—76, wire 77, windings 70 of safety magnet S^a , wire 78, through the negative bus, wire 113, windings of safety magnet S^b , wire 121, contacts 122—123—124 of polarized relay P^b , wire 125, to the left-hand terminal of the secondary of local transformer LT^b . The current, which would flow through this circuit, should such a cross 75 occur, is of insufficient value to operate relay SS^a . This is determined by the provision of the safety magnets S^a and S^b positioned in the common or negative return wires of the respective switch machine function, as their 80 combined impedance adds to the regular impedance in the line phase winding circuit of the relay SS^a , an amount sufficient to limit the current which may flow therein to a value beneath the operating value of such an SS relay.

If a cross should occur between wire 56 and wire 68, the line phase winding 30 of the SS^a relay would be shunted in a manner to cause its deenergization. Also, it would be necessary for a break to occur in wire 56 and a break in wire 68 with these broken wires connected together in a reverse manner in order for a false active indication to be displayed by the relay SS^a . As is well known to those skilled in the art, such an occurrence is very 95 remotely possible. If such a case did occur, it would be immediately detected upon the next operation of the control lever.

Thus, the present invention provides an interlocking system, which is effectively protected from crosses that may occur within the control circuits of a particular function, and which is effectively protected from crosses from other remotely controlled functions. The present invention further provides a superimposed alternating current indication system for giving a reliable indication of the 105 position and locked condition of its associated switch machine, which system checks the cross protection circuits of the switch machine, as well as, in itself being protected from crosses with other similar indication systems.

110 Although the operation of the switch machine function SM^a has been more specifically pointed out, and although the relationship of this function has been more specifically pointed out with reference to the switch machine function SM^b , it is to be understood that converse conditions are also true. In the application of such switch machine functions, it is probable that a large number of such 115 functions would be operated from the same positive and negative buses, thus making pos-

sible innumerable combinations of unauthorized conditions, which it is obviously impossible to specifically point out. However, those specific abnormal conditions which 5 have been pointed out are to be considered as merely illustrative of those other conditions which might occur. In other words, it is intended that a particular switch machine function is to be protected from improper operation or indication by the application of unauthorized positive potential, that is, a potential, which is positive in respect to the negative bus, to its next operating wire regardless of its present position, 10 whether such potential may be applied from another similar function in a similar position or in a different position or from any foreign source. Protection of an SS relay from operation from the energizing source of 15 any other similarly operated SS relay is to be provided regardless of the positions of the functions involved in the unauthorized cross circuits.

Having described an indication system of 20 one type as superimposed upon an interlocking system for purposes heretofore set forth, as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form 25 shown to meet the requirements of practice, without in any manner departing from the spirit or scope of the present invention except as limited by the appended claims.

Having described my invention, I now 30 claim:

1. In an interlocking system for railroads, a track switch, a switch machine, a control lever, two operating wires and a common return wire inter-connecting said switch machine and said control lever, contacts operated by said lever to establish normal and reverse control circuits, also normal and reverse dynamic indication circuits, a source of electrical potential having positive and negative terminals, an indication selector having normal and reverse operating coils included in said normal and reverse control circuits respectively and having contacts included in said normal and reverse dynamic 45 indication circuits, an indication magnet included in said normal and reverse indication circuits, a cross protection relay included in said normal and reverse indication circuits, and a safety magnet included in the common 50 connection of said control circuits to the negative terminal of said source and not included in said common wire.

2. In an interlocking system for railroads, a track switch, a switch machine, a control lever, two operating wires and a common return

wire inter-connecting said switch machine and said control lever, contacts operated by said lever to establish normal and reverse control circuits, also normal and reverse dynamic indication circuits, a source of direct current electrical potential having positive and negative terminals, an indication selector having normal and reverse operating coils included in said normal and reverse control circuits respectively, and having contracts included in said normal and reverse dynamic indication circuits, an indication magnet included in said normal and reverse indication circuits, a cross protection relay included in said normal and reverse indication circuits, a safety magnet included in the common connection of said control circuits to the negative terminal of said source and not included in said common wire, an electro-responsive device included in said dynamic indication circuit which device is not responsive to dynamic indication current, and means applying energizing current to said dynamic indication circuit to which said electroresponsive device will respond and thereby indicate the condition of said track switch.

3. In an interlocking system, a track switch, a switch machine, a control lever, a source of electrical energy, means for completing normal and reverse control circuits from said source to said switch machine, means for completing normal and reverse dynamic indication circuits, dynamic indication responsive means for governing the movement of said control lever included in said normal and reverse dynamic indication circuits, an electroresponsive device included in said dynamic indication circuit but unresponsive to dynamic indication current, alternating current energizing means for actuating said electroresponsive device in accordance with the condition of said track switch but ineffective for actuating said dynamic indication responsive means, and safety means for preventing the operation of said dynamic indication responsive device during the flow of current in said control circuits, and during the flow of current in said indication circuits when said flow is opposite to the normal direction of flow of said dynamic indication current, and for preventing the flow of alternating current from said energizing means to said source of electrical energy.

4. In combination with electric interlocking systems of the type as shown and described, superimposed alternating current indication systems, each of said indication systems comprising, an electro-responsive device responsive to alternating current only, said device having a local phase winding and a line phase winding, means for energizing said local phase winding, means for energizing said line phase winding in ac-

cordance with the condition of a particular interlocking system, means for relatively adjusting the phase displacement between the currents in said local and said line phase 5 windings, and cross protection means protecting each one of said indication systems from every other one of said indication systems.

5. In an interlocking system for railroads, 10 a track switch, a switch machine having an armature and a field winding, a control lever, two operating wires and a common return wire, a source of direct current electrical potential having positive and negative terminals, contacts operated by said control lever for establishing normal and reverse operating circuits, also normal and reverse dynamic indication circuits for said switch machine over said operating wires and said common 15 return wire, an indication selector having normal and reverse operating coils included respectively in said normal and reverse operating circuits and having contacts included in said normal and reverse dynamic indication 20 circuits, an indication magnet included in said dynamic indication circuits, a safety magnet included in the common connection of said operating circuits to said negative terminal of said source of direct current potential, a polarized relay included in said dynamic indication circuits and unresponsive to the dynamic indication current flowing therein but responsive to current of an opposite polarity, said relay having contacts 25 for opening said common connection of said operating circuits to said negative terminal of said source, an alternating current electro-responsive device included in said dynamic indication circuits only and being unresponsive 30 to direct current, means for superimposing alternating current upon said dynamic indication circuits in accordance with the position of said track switch, means for relatively adjusting the ratio between the reactive and resistive current components of said 35 alternating current used to actuate said alternating current electro-responsive device, said means including a resistance in multiple with said field winding and another resistance 40 in series with said means for superimposing alternating current upon said dynamic indication circuits.

6. In an interlocking system; the combination with a switch machine; a lever; a normal and a reverse control wire and a common wire leading from said lever to said switch machine; a dynamic indication magnet; a safety magnet acting in opposition to said indication magnet; a source of current; a 55 normal circuit for said switch machine including said normal wire, said common wire, said safety magnet and said source in series, and with said safety magnet in the lead wire from one terminal of said source; a reverse 60 circuit for said switch machine including said 65

reverse wire, said common wire, said safety magnet and said source in series, and with said safety magnet in said lead wire; and an indication circuit including said reverse wire, the motor of said switch machine, said common wire and said indication magnet in series, and with said lead wire connected to the junction of said common wire with said indication magnet, whereby if unauthorized current flows through said indication magnet and to said source it also flows through said safety magnet and prevents operation of said indication magnet.

7. In an interlocking system; the combination with a switch machine; a lever; a normal and a reverse control wire and a common wire leading from said lever to said switch machine; a dynamic indication magnet; a safety magnet acting in opposition to said indication magnet; a source of current; a normal circuit for said switch machine including said normal wire, said common wire, said safety magnet and said source in series, and with said safety magnet in the lead wire from one terminal of said source and said common wire connected to said lead wire; a reverse circuit for said switch machine including said reverse wire, said common wire, said safety magnet and said source in series, and with said safety magnet in said lead wire; and an indication circuit including said reverse wire, the motor of said switch machine, said common wire and said indication magnet, whereby if unauthorized current flows through said indication magnet and to said source it also flows through said safety magnet and prevents operation of said indication magnet.

In testimony whereof I affix my signature. 105
JOHN C. LINDNER.
